UNITED STATES PATENT OFFICE.

FREDERICK W. LEITENBERGER, OF READING, PENNSYLVANIA, ASSIGNOR TO READING STANDARD COMPANY, OF READING, PENNSYLVANIA, A CORPORATION OF PENNSYLVANIA.

SPARKING CUT-OUT FOR INTERNAL-COMBUSTION ENGINES.

No. 893,333.

Specification of Letters Patent.

Patented July 14, 1908.

Application filed November 25, 1907. Serial No. 403,627.

To all whom it may concern:

Be it known that I, FREDERICK W. LEITENBERGER, a citizen of the United States, and a resident of the city of Reading, in the county of Berks and State of Pennsylvania, have invented certain new and useful Improvements in Sparking Cut-Outs for Internal-Combustion Engines, of which the following is a specification.

10 My invention relates to controlling mechanism for internal combustion engines, and more particularly to improved means for automatically cutting out the spark current simultaneously with the movement of the 15 sparking device to extreme retarding position and the holding of the engine controlling valve in inoperative position.

The invention is fully described in connection with the accompanying drawing and is 20 specifically pointed out in the claims.

Figure 1 is a side elevation showing the crank-casing portion of an internal combustion engine having my invention applied thereto; a portion of the cam-box being 25 broken away and the cover plate of the oscillating contact-breaker casing removed. Fig. 2 is a separate view showing the contact finger and cut-out fulcrum in different positions from Fig. 1; and Fig. 3 is a rear view of the 30 contact-breaker casing showing the cut-out lever.

The internal combustion engine indicated has a cylinder 1 provided with intake and exhaust valves having parallel vertically 35 guided stems 4 and 5 both of which are operated from the engine crank shaft 6 mounted in the crank casing 7. This construction, as well as the direct drive connection of the cam shafts 10, 11 and 12 with the main shaft 6; 40 the means for operating the valves from said cam shafts; and the general arrangement and operation of the sparking mechanism with its contact-breaker casing 22 rotatably mounted upon the cam shaft 12 and adapted 45 to independently act upon the exhaust valve stem 5 through a slide-pin 24 and a bell crank 23;—form no part of my invention.

The object of my invention is to provide an improved construction whereby the electric 50 sparking circuit will be automatically opened simultaneously with the action upon the controlling valve which occurs when the contact breaker casing 22 is moved to its ex-

treme spark-retarding position, thereby greatly prolonging the life of the batteries, 55 and contact points.

The breaker-casing 22 is provided with an exterior valve operating arm or projection 25; with an interiorly projecting contact-point 30, adjustably fixed in the insulated 60 casing wall 31 and connected exteriorly to a battery wire 32 as usual; and with a yielding contact finger 33 pivoted at 34 within the casing and adapted to be normally pressed into and out of contact, midway of its length, 65 with the point 30 during each turn of the contact-breaker cam 21 operating upon its end 35; this general construction, as well as the mounting of the casing 22 upon the cam shaft 12 and the operation of the same by 70 the rider to vary the timing of the spark and finally hold open the controlling valve of the engine, being old and well known. My invention consists in automatically preventing the unnecessary making and breaking of the 75 igniting circuit while the controlling valve is thus held open by the casing 22, by providing a cut-out in said casing whereby the contact finger 33 is prevented from being moved into contact with the point 30 by the action of 80 the contact-breaker cam; said cut-out consisting as shown of a fulcrum-cam 36 rotatably mounted in the wall of the casing 22, and provided with an exterior lever 37 adapted to be swung with the casing into 85 contact with a fixed abutment, as for instance the cam-box on the crank casing, and thereby cause the fulcrum-cam 36 to be turned so that it will project beyond the point 30 and hold the yielding finger 33 away 90 from the latter notwithstanding the continued action of the contact-breaker cam upon said finger. This movement of the fulcrum-cam is effected against the tension of a spring 38 which normally holds it in 95 retracted position where the finger 33 is free to contact with the point 30; and the movement occurs simultaneously with the holding-open action of the casing 22 upon the controlling valve, so that the igniting circuit 100 is automatically held open with the latter, until the casing 22 is reversely moved by the rider. It will be readily seen that all wastage of the batteries and unnecessary wear of the contact points is thus automatically prevented by the very simple and inexpensive

mechanism described, the specific construction of which may obviously be modified without departing from my invention.

What I claim is:

- 5 1. A sparking device for internal combustion engines comprising an oscillatingly mounted casing provided with a fixed contact-point, a yielding contact-finger adapted normally to be swung into contact with said point, and a cut-out fulcrum movably mounted in the casing adjacent said point substantially as set forth.
- 10 2. In an internal combustion engine having a controlling-valve, operating mechanism therefor, and a contact-breaker cam, an adjustable sparking mechanism comprising

an oscillating contact-breaker casing having a fixed contact-point, a yielding contact finger operated by said cam, and a cut-out fulcrum for said finger removably mounted in the casing and provided with an operating arm, said controlling valve and cut-out fulcrum being simultaneously acted upon by the movement of said casing to extreme spark-retarding position substantially as set forth.

In testimony whereof I affix my signature in the presence of two witnesses.

F. W. LEITENBERGER.
